UNITED STATES PATENT OFFICE.

WILLIAM DEVERAUX, OF CHICAGO, ILLINOIS.

BRIDGE-GATE.

SPECIFICATION forming part of Letters Patent No. 309,697, dated December 23, 1884.

Application filed July 25, 1884. (No model.)

To all whom it may concern:

Be it known that I, WILLIAM DEVERAUX, a citizen of the United States, residing at Chicago, in the county of Cook and State of Illinois, have invented certain new and useful Improvements in Bridge-Gates, of which the following is a specification, to wit:

This invention relates to an improvement in bridge-gates; and it consists in certain peculiarities of the construction and arrangement of the same, substantially as will be herein-after more fully set forth and claimed.

In order to enable others skilled in the art to which my invention appertains to make and use the same, I will now proceed to describe its construction and operation, referring to the accompanying drawings, in which—

Figure 1 is a plan view of a portion of the bridge and the adjoining approach. Fig. 2 is a cross-section of the approach. Fig. 3 is a front elevation of the approach and the gate-operating mechanism; Fig. 4, an end view of the bridge, and Figs. 5 and 6 are details of parts of the operating devices.

25 A represents a bridge of the common and well-known form, pivoted in the center and swinging entirely around to allow of the passage of vessels. This bridge is upon each end provided with two toothed racks, A' A'', the former of which is placed near one corner under the roadway, and the latter in rear of and below the other, and commencing at the inner end of the first rack and running in toward the center of the bridge, as clearly shown in Fig. 4.

35 In suitable bearings in the end of the abutment or approach is journaled a shaft, b, upon the outer end of which is a lantern-wheel, B, which is engaged and operated by the rack A'. Beside and below this shaft is a second one, b', the outer end of which is provided with a lantern-wheel, B', projecting in front of the other, and these wheels are each provided with cogs or teeth b'', meshing together as represented, by which one gives motion to the other, as 45 will be presently explained.

Upon the inner end of the shaft b is a pinion, b³, engaging a rack, c, upon a vertically-sliding bar, C. This bar is near its lower end provided with a second rack, c', engaging a 50 pinion, d, upon a shaft, D, running across the

abutment, and having a similar pinion, d, upon its opposite end, engaging and operating a rack, c', upon a second vertically-sliding bar, C', as shown in the drawings. The bars C C' are incased in a suitable frame or casing, and are at their upper ends each provided with racks c² c'', engaging with and giving motion to a segment-gear, E, upon a shaft, e, journaled in this frame, upon the ends of which are secured the arms E', which form the gate across 55 the roadway when they are lowered, and when not in use stand in a vertical position, as in Fig. 5.

A second gate, E'', is hinged in each casing F upon a short shaft, F', and arranged to swing 60 across the foot-walk as the road-gates descend by a bevel-wheel, f, upon the shaft F' meshing with a similar pinion, f', upon the shaft e.

In the center of the roadway is a vertical bar, G, which rises and falls in the approach, 70 and has upon its lower end a rack, g, meshing with a gear-wheel, d', upon the shaft D, and having its upper end bifurcated to receive and support the ends of the arms E', as in Fig. 2.

In operation, when the bridge is closed, the 75 gates are open, as in Fig. 1, and when the bridge begins to swing open in one direction the rack A' operates the lantern-wheel B, and by means of the pinion b³ and rack c draws down the bar C. This bar, by its rack c' and 80 the shaft D, operates the bar C' at the opposite side of the roadway, so that they slide down together. These two bars operate the shafts e and F' and close the gates E' E'', and prevent accident to both foot-passengers and teams. 85 At the same time the gate-arms E' fall, the wheel d' lifts the supporting-bar G to meet them, and as this bar rises as the arms fall it is evident that any weight upon the arms only tends to more firmly lock them in connection 90 with their supports. The gates are thus closed before the bridge has swung more than a few feet, and all accidents prevented. When the bridge is closed again, if swung back to its first position the operation is reversed; but if 95 turned entirely around the rack A'' engages the lantern-wheel B', and it operates the wheel B and its connecting devices in the reverse direction to open the gates, as will be at once understood.

Having thus fully described my invention, what I claim as new, and desire to secure by Letters Patent, is—

1. In a bridge-gate, the combination, with the gate and a series of rack-bars and gearing, of two lantern-wheels geared together, and one projecting beyond the other, and two operating-racks upon the bridge, one in front of the other, whereby the gates are operated by the bridge in either direction, substantially as shown and described.
2. In a bridge-gate, the combination, with two hinged arms raised or lowered over the roadway by mechanism operated by the bridge, of a supporting-bar sliding vertically through the center of the roadway to support the gate-arms when lowered, substantially as shown and described.
3. The bridge A, provided with the racks A' A'', one in front of and above the other, in combination with two lantern-wheels, B B',

upon shafts journaled in the approach, and having teeth b², meshing together, the rack-bars c c', connected by shaft D, to operate together, the segment E, shaft e, and arms E', secured upon its ends, substantially as and for the purpose set forth.

4. The shaft b, carrying the lantern-wheel B and pinion b³, the sliding rack-bars C C', connected by the shaft D and pinions d d, the segments E, shafts e F', gates E' E'', and bevel-wheels f f', in combination with a gear, d', upon the shaft D, and a vertically-sliding rack-bar, G, operated thereby to receive and support the gate-arms E', substantially as and for the purpose set forth.

In testimony whereof I affix my signature in presence of two witnesses.

WILLIAM DEVERAUX.
